UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

NONAGITATING COOKER.

Application filed December 28, 1924. Serial No. 758,315.

To all whom it may concern:

Be it known that I, ALBERT R. THOMPSON, a citizen of the United States, residing at San Jose, in the county of Santa Clara and State of California, have invented certain new and useful Improvements in Non-agitating Cookers, of which the following is a specification.

My invention relates, in general, to the 10 canning art, and in particular to can-handling machines, devices and apparatus used in the art for conveying the product filled containers in and through a definite path for some purpose or object dependent upon the 15 particular method or process being employed.

Although such appliances and their several purposes are of varied character, I shall herein refer, as best illustrative of 20 my present improvement, to those machines known in the art as "cookers" but it will be understood, from the object I have in view, that my invention is applicable to other can-handling machines and devices 25 wherein, for any purpose, the product filled containers are carried in and through a predetermined path.

A cooker, briefly described, is a machine comprising a casing or shell having an inlet to which the filled cans are fed and an outlet from which they are discharged; means within the shell for advancing the cans from the inlet to the outlet; and means for subjecting the cans to heat during their 35 progress through the shell. The path of progress varies with the special type of machine as does also the advancing means, but in the type of cooker which for illustration I have herein selected, the path is a helical one and the conveying means comprises a reel of can carrying rails revoluble about a horizontal axis, and circumscribed by a helically directed fixed rail. Cookers of this type are now well known and 40 are extensively used, and, therefore, need no special description in full detail.

In the canning art, it was early found that in processing the filled cans, especially in cookers, it was of advantage to cause 45 each can in addition to its major revolution with the reel, to roll on its axis while advancing in the treating path thereby more fully agitating the can contents and thus providing for an equable heat subjection.

This rolling of the cans has been effected 55 in various ways, and in the type of cooker herein illustrated the means employed are simple and direct, the result of the peculiar structure of the path through which the cans pass. The cans, lying freely endwise 60 in the carrying rails of the rotating reel and their ends in contact with adjacent coils of the helically directed fixed rail, are carried around by said reel in successive major revolutions inclined to the reel axis. But 65 since the cans peripherally lie between the bases of the reel rails and the foot flanges of the fixed helical rail, they roll upon said foot-flanges, each can thus having a rotation 70 upon its own axis in addition to its general or major revolution about the reel axis, such additional rotation being less pronounced and even absent in the upper arc of revolution since in this region the cans rest by gravity upon the reel rails and are 75 in slight contact or not at all, with the foot flanges of the fixed helical rail, while in the lower arc of revolution, the cans rest by gravity wholly upon said foot flanges.

It has since been found, however, the 80 agitation as the result of this rolling is not wholly desirable in treating certain kinds of food products. For example in canning peas the agitation is a detriment, in that it clouds the liquor content of the can, which 85 effect, for want of a better explanation, I ascribe to the separating out of starchy matter; and in the canning of tender berries, the effect of the agitation is to break them down.

In the case of peas, particularly, the season is a short one, and if increasing the volume passing through the cooker be resorted to, the machine itself must be lengthened to meet the increase, and this only 90 heightens the undesirable effect of the agitation, and materially adds to the cost of the machine.

In the light of the foregoing my present improvement and its object will readily be 100 understood.

My object is to provide a machine of the type above referred to, which while conveying the filled cans in the helical path found in practise to be efficient, will prevent the cans from independently rolling on their individual axes, thus eliminating all agitation except that which may result

from their main or major revolution about the reel axis, which is negligible, and is perhaps even beneficial.

To this end my invention consists in the 5 novel non-agitating can handling machine or apparatus, which for convenience I have herein entitled a cooker, and which I shall now fully describe by reference to the accompanying drawings, in which—

10 Fig. 1 is a longitudinal section, broken at both ends, of the machine.

Fig. 2 is an end view of the same.

In the drawings, I have not attempted to show in full a complete cooker, since such 15 detail is not essential to a full understanding of my improvement. Therefore, I have omitted the general frame, the driving mechanism, the treating medium and the means for applying said medium.

20 1 is the casing or shell of the machine. 2 is a rail fixed to the inner surface of the shell and helically directed therein from end to end. This rail, in practise, is best formed of T-section, with its leg flange extending inwardly and its foot flanges lying 25 parallel with the shell wall, as seen in Fig. 1.

3 is a rotatable shaft extending through the shell in its axis. Upon this shaft are fixed heads one of which designated by 4 30 is here shown.

Carried by the periphery of these heads are the can supporting rails 5. These are best formed of angle section, as seen in Fig. 2, with one flange extending radially outwardly and the other lying upon the head periphery. There is an annular series of these rails spaced apart and extending parallel with the axis of revolution.

The shaft 3, heads 4 and rails 5 thus 40 constitute a reel rotatable about a horizontal axis and lying within the fixed helically directed rail 2. All these parts are those usual to this type of machine, and they are so related as to form the usual helical can path, 45 the cans indicated by 6, in dotted lines, lying between the reel rails 5 and the fixed rail 2, the periphery of the cans being surrounded by said rails and the outer portions of the ends of the cans being flanked by the 50 inwardly extending flanges of the coils of the fixed rail.

My improvement consists in means for preventing contact of the can periphery during the revolution of the can about the reel 55 axis with any surface of the can path fixed with relation to said revolution. This fixed surface might be the inner surface of the shell itself, in case the helically directed rail be a single inwardly extending member, 60 but in the case here shown in which said

rail is of T-section, said fixed surface comprises the foot flanges of said rail.

The means here shown for thus positioning the can in its path comprise guard members 7 with which the outer edges of the 65 radial flanges of the reel rails 5 are provided. These guard members are shaped and positioned to permit the can periphery to protrude sufficiently to enable the ends of the can to be engaged by the inwardly extending flanges of the coils of the fixed rail 2, but not sufficiently to allow said periphery to contact with the foot flanges of said rail. These guard members 7 while not functioning during the upper arc of the major revolution, function in full during the lower arc 70 of said revolution, and positively hold and support the can periphery out of contact with the foot flanges of the fixed rail 2, whereas if they were not present, the can 75 would, while passing through said lower arc of revolution, fall to and rest upon said foot flanges and so roll on its own axis. But with the guard members such contact rolling is prevented.

I claim:—

1. A can-handling machine comprising an outer shell; an inwardly extending fixed can-advancing rail within the shell and helically directed throughout its length; a reel 90 of horizontally directed outwardly extending can-carrying rails mounted within the shell and rotatable within the fixed rail about the axis thereof, said fixed and rotatable rails constituting means for receiving and advancing the cans in a helical path through the shell; and means for holding the cans in the can-carrying rails out of peripheral contact, during their revolution, 95 with a fixed surface of said path, to prevent them from rolling thereon.

2. A can-handling machine comprising an outer shell; an inwardly extending fixed can-advancing rail within the shell and helically directed throughout its length; a reel 105 of horizontally directed outwardly extending can-carrying rails mounted within the shell and rotatable within the fixed rail about the axis thereof, said fixed and rotatable rails constituting means for receiving and advancing the cans in a helical path through the shell; and guard members carried by the outer edges of the reel rails for holding the cans, during their revolution with the reel, out of peripheral contact with a fixed surface of said path, to prevent them 110 from rolling thereon.

In testimony whereof I have signed my name to this specification.

ALBERT R. THOMPSON.
